US00D947226S

(12) **United States Design Patent** (10) Patent No.: **US D947,226 S**
Chaudhri et al. (45) Date of Patent: **** *Mar. 29, 2022**

**(54) DISPLAY SCREEN OR PORTION THEREOF
WITH GRAPHICAL USER INTERFACE**

(56) **References Cited**

U.S. PATENT DOCUMENTS

(71) Applicant: **Apple Inc.**, Cupertino, CA (US)

(72) Inventors: **Imran Chaudhri**, San Francisco, CA (US); **Marcel van Os**, Santa Cruz, CA (US)

(73) Assignee: **Apple Inc.**, Cupertino, CA (US)

(*) Notice: This patent is subject to a terminal disclaimer.

(**) Term: **15 Years**

(21) Appl. No.: **29/732,673**

(22) Filed: **Apr. 27, 2020**

Related U.S. Application Data

(63) Continuation of application No. 29/443,590, filed on Jan. 18, 2013, now Pat. No. Des. 882,599, which is a continuation of application No. 29/379,178, filed on Nov. 16, 2010, now Pat. No. Des. 680,125.

CLAIM

The ornamental design for a display screen or a portion thereof with graphical user interface, as shown and described.

DESCRIPTION

FIG. 1 is a front view of a display screen or portion thereof with graphical user interface showing the claimed design; FIG. 2 is a second embodiment thereof; FIG. 3 is a third embodiment thereof; and, FIG. 4 is a fourth embodiment thereof.

The outermost broken lines in the figures show a display screen or portion thereof, and form no part of the claimed design. The other broken lines in the figures show portions of the graphical user interface that form no part of the claimed design.

1 Claim, 4 Drawing Sheets
